Primary Examiner — Christy Nemeth(74) *Attorney, Agent, or Firm* — MUNCY, GEISSLER,
OLDS & LOWE, P.C.(57) **CLAIM**

The ornamental design for an electric vehicle charger as shown and described.

DESCRIPTION

FIG. 1 is a front view of an electric vehicle charger showing my new design;

FIG. 2 is a rear view thereof;

FIG. 3 is a left side view thereof;

FIG. 4 is a right side view thereof;

FIG. 5 is a top plan view thereof; and,

FIG. 6 is a bottom plan view thereof.

The broken lines in the drawings illustrate portions of the electric vehicle charger that form no part of the claimed design.
